UNITED STATES PATENT OFFICE

ANDREW D. WYCKOFF, OF FORT WAYNE, INDIANA, ASSIGNOR TO S. F. BOWSER & COMPANY, INCORPORATED, OF FORT WAYNE, INDIANA, A CORPORATION OF INDIANA.

PUMP.

1,126,167.

Specification of Letters Patent.

Patented Jan. 26, 1915.

Application filed March 27, 1911. Serial No. 617,098.

To all whom it may concern:

Be it known that I, ANDREW D. WYCKOFF, a citizen of the United States, residing at Fort Wayne, in the county of Allen and State of Indiana, have invented certain new and useful Improvements in Pumps, of which the following is a specification.

This invention relates to improvements in liquid pumps, particularly adapted though not necessarily limited in its use for supplying or discharging liquid, such as oil, to a remote container and from which latter the liquid may be dispensed, and the primary object of this invention is to provide an improved pump of this class having means whereby it may be supplied with liquid from any suitable source and also means whereby the pump may be set to discharge a predetermined quantity of liquid to the container; a further object being the provision of an improved pump of this class having means whereby the discharge to the container may be automatically cut off or stopped when the predetermined quantity has been discharged.

A further object is the provision of an improved pump of this class having means whereby access to the discharge controlling mechanism by unauthorized persons may be prevented.

A further object is the provision of an improved pump of this class having means whereby liquid may be dispensed at the pump when the discharge or supply to the remote container is cut off.

A further object is to provide an improved pump of this class which will be simple, durable and cheap in construction and effective and efficient in operation.

To the attainment of these ends and the accomplishment of other new and useful objects, as will appear, the invention consists in the features of novelty substantially in the construction, combination and arrangement of the several parts hereinafter more fully described and claimed and shown in the accompanying drawings exemplifying the invention, and in which—

Figure 1 is a side elevation of an improved pump of this class constructed in accordance with the principles of this in-

vention. Fig. 2 is a top plan view of Fig. 1. Fig. 3 is a sectional view on line 3—3, Fig. 1. Fig. 4 is a side elevation, similar to Fig. 1, of the controlling mechanism whereby the supply to the remote container may be cut off, showing parts in section and with the inclosing casing also in section. Fig. 5 is a sectional view on line 5—5, Fig. 9. Fig. 6 is a sectional view on line 6—6, Fig. 9. Fig. 7 is a sectional view taken on line 7—7, Fig. 4. Fig. 8 is a sectional view taken on line 8—8, Fig. 10, with parts broken away. Fig. 9 is a sectional view on line 9—9; Fig. 7. Fig. 10 is a sectional view taken on line 10—10, Fig. 7.

Referring more particularly to the drawings and in the present exemplification of the invention the numeral 15 designates generally a pump cylinder supported upon a base 16 and having a supply pipe 17 for supplying liquid to the cylinder. Within the cylinder 15 is arranged a piston 18 which is adapted to be reciprocated therein by means of a rack 19 secured to the upper extremity of the piston rod 20 and this rack passes through a suitable guide 21 supported preferably by the cylinder head.

A pinion 22 is secured to a shaft 23 which latter is journaled in suitable bearings and is arranged so that the pinion 22 will mesh with the rack 19. The piston is so arranged and constructed that when the pinion 22 is rotated in one direction to raise the rack 19 and the piston 18, the liquid will be discharged through the head 24. During this upward movement of the piston 18 a fresh supply of liquid will be drawn into the cylinder 15 on the under side of the piston 18, so that when the pinion 22 is rotated in the opposite direction to lower the rack 19 and the piston 18 the liquid will pass by the piston to the opposite side thereof to be discharged through the head 24 when the piston is again raised. The specific construction and operation, however, of this portion of the mechanism forms no part of the present invention but is simply described as a convenient and simple form of pump to which the improved mechanism which will now be described is attached.

The head 24 of the cylinder is provided

with a discharge outlet 25 and connected with this outlet to have communication therewith is a discharge pipe 26, which latter extends to any suitable point of use, such as a remote container, which latter is usually located in a pit or well. Arranged within this pipe 26, and beyond the outlet 25 is a valve casing designated generally by the reference numeral 27 to the outlet 28 of which is connected the pipe 26. The inlet 29 of the valve housing is also connected with a portion of the pipe 26 as shown more clearly in Fig. 3.

A valve seat 30 is arranged within the valve housing 27 with which a valve 31 operates.

An elastic member 32 such as a coil spring or the like, is provided, one end of which has connection with the valve 31 and the other end rests within a cap 33. This cap 33 is removably secured to the valve housing 27 so as to close an opening therein, as shown, and serves as a means whereby access may be had to the valve 31. The normal tendency of this elastic member 32 is to move the valve 31 against its seat 30 so as to shut off the flow of liquid through the valve housing.

A valve stem 34 is provided on the valve 31 and this stem passes through a suitable bushing or packing box 35 and preferably projects above or beyond the valve housing 27.

A casing 36 is provided for protecting the end of the stem 34 and this casing may be of any desired size and construction, the lower end 37 of which is provided with internal screw threads adapted to coöperate with screw threads on the portion 38 of the valve housing.

The casing 36 is provided with an opening 39 in the top thereof and the casing is preferably of some length. Projecting through the opening 39 in the top of the casing is a bushing 40 having a shoulder 41 engaging the inner face of the top of the casing and a nut 42 surrounds the bushing 40 and co-operates with peripheral screw threads thereon to serve as a means whereby the bushing 40 may be secured against displacement with respect to the casing 36. This bushing 40 is provided with an opening having communication with the interior of the casing 36 and is provided with internal screw threads 43 with which screw threads on one extremity of a tubular member 44 co-operate to secure or connect the tubular member 44 with the casing 36. This tubular member 44 may be of any desired diameter and length but is preferably of a length so that its upper end will terminate adjacent the guide 21. The upper extremity of the tubular member is also provided with peripheral screw threads, and the end is adapted to project into a threaded boss 45

on a casing 46, which latter may be secured to or supported by the pump frame in any desired or suitable manner, and is provided for the purpose of housing the controlling mechanism, to be presently described.

Projecting through one of the walls of the housing 46 and journaled in a suitable bearing 47 is a shaft 48, one extremity of which projects for some distance into the housing and is provided with a worm gear 49 on the extremity thereof. The bearing 47 is secured against displacement in any desired or suitable manner, preferably by means of a fastening device 50. The extremity of the bearing which is located outside of the housing 46 is provided with a flange 51 having a recess 52 in the outer face thereof, and the shaft 48 is of such a length that the end 53 thereof will project through the recess 52 and beyond the outer face of the flange 51.

Arranged within the recess 52 is a ratchet member 54 having faces 55 which coöperate with the wall of the recess 52. Rollers 56 are arranged within the recess 52 adjacent the faces 55 of the ratchet element 54 and a shoulder 57 is also provided in the ratchet element 54 for each of the faces 55.

An elastic member 58 is disposed between each of the faces 57 and the respective rollers 56 and tend normally to force the rollers 56 against the wall of the recess 52. When the shaft 48 is rotating in the direction indicated by the arrow in Fig. 6, the springs 58 will be compressed to a certain extent and the member 54 will force the rollers 56 around the recess 52. If, however, the shaft 48 is rotated in a direction opposite to the direction indicated by the arrow in Fig. 6, the faces 55 will force the rollers 56 into engagement with the wall of the recess 52 and thereby lock the shaft 48 against rotation. The ratchet of element 54 is secured to the shaft 48 for rotation therewith in any suitable manner, preferably by means of the fastening key 58. A similar ratchet element 59 (see Fig. 5) is also keyed to the shaft 48 by means of the fastening key 58 but this ratchet element 59 is located outside of the recess 52, and is provided with faces 60 corresponding to the faces 55 of the element 54 and shoulders 61 corresponding with the shoulders 57 of the element 54. These ratchet elements are preferably of substantially the same diameter and arranged to inclose the ratchet element 59 is a sleeve 62, the peripheral flange 63 of which extends over the periphery of the element 59, as shown more clearly in Figs. 5 and 9.

Friction rolls 64 similar to the rolls 56 are provided in each of the spaces formed by the shoulders 61 and faces 60 of the element 59, and elastic members 65 are also provided between the shoulders 61 and the

70

85

90

95

100

105

110

115

120

125

130

respective rolls 64. The faces 60 and shoulders 61 of the element 59 are preferably located slightly in advance of the shoulders 57 and the faces 55 of the element 54. The 5 sleeve 62 is secured for rotation to a shaft 66 and one end of this shaft 66 abuts the end 53 of the shaft 48. Bracket 21 is provided for the casing 46 and the shaft 66 is held in position in any desired or suitable manner, 10 preferably by means of fastening devices 68, such as cap screws, which pass through flange 51 and the member 67 and screw into the bracket 21.

From the mechanism thus far described, 15 it will be apparent that when the shaft 66 is rotated in one direction, or a direction to cause the peripheral flange 63 to rotate in the direction indicated by the arrow in Fig. 5, the rolls 64 will be forced against the 20 faces 60 of the element 59 so that the latter will be locked for rotation by the peripheral flange 63 and as this element 59 is fast to the shaft 48, it will be apparent that the shaft will also be rotated. During this rotation of the peripheral flange 63, and consequently of the shaft 48, the element 54 will be rotated in the direction indicated by the arrow in Fig. 6, and the shoulders 57 will tend to compress the springs 58 to 25 force the rolls 56 around the wall of the recess 52. When the direction of rotation of the shaft 66 is reversed, the peripheral flange 63 will tend to force the rolls 64 in a direction toward the shoulders 61 to 30 compress the elastic members 65 and this will permit the peripheral flange 63 to rotate independently with respect to the shaft 48 and also the element 59. During this reverse rotation of the peripheral flange 63, any 35 tendency of the shaft 48 to rotate in the opposite direction will be overcome by the element 54 as this element will also tend to rotate in the opposite direction to cause the faces 55 thereof to force the rolls 56 against the wall of the recess 52 to bind or lock the 40 element 54 against rotation.

The shaft 66 may be rotated in any desired or suitable manner, preferably by means of a crank or handle 69 and in order to impart the rotation of the shaft 66 to the pinion 22 which raises and lowers the rack 19 and consequently the piston 18, a gear 70 is provided on the shaft 66 which meshes with a gear 71 secured to the shaft 55 23, as clearly shown in Fig. 1.

Arranged within the housing 46 and projecting preferably from the rear wall thereof is a stud or axle 72 and this stud or axle passes eccentrically through a hub 73 of a 60 drum 74. The hub 73 preferably projects for some distance beyond each side of the drum 74, and the drum is provided with an open side preferably disposed toward the rear wall of the housing 46.

Arranged within the housing and through

which the stud or axle 72 passes is an element 76 preferably in the form of a bracket having a flanged portion 77 and a hub 78 against which one extremity of the hub 73 of the drum 74 rests. The spring drum is 70 held against accidental displacement with respect to the stud or axle 72 in any desired or suitable manner, preferably by means of a fastening device 78 which passes into the free end of the axle and through a washer 75 79 which is of a diameter to project over the edges of the axle.

Mounted to rotate loosely upon the hub 73 of the spring drum, and preferably between the drum and the element 76 is a worm gear wheel 80 which is provided with a hub 81. The hub 81 is preferably of such a length that one extremity will rest against the projection 78 of the element 76 and the other end will project into the drum 74 through the open side thereof. The drum 74 is preferably of a diameter somewhat larger than the diameter of the hub 81 of the gear 80 and an elastic member 82, preferably in the form of a coil spring is arranged within the drum and is coiled about the adjacent portion of the hub 81 of the gear 80. One extremity of the spring is secured as at 83 to the hub 81 of the gear 80 and the other extremity of the spring is 95 secured as at 84 to the drum.

Arranged upon the element 76 and projecting toward the gear 80 is a projection or extension 85 which is preferably provided with a recess adapted to receive an elastic member 86 which latter is preferably in the form of a coil spring. This spring is of such a length that one extremity will normally project beyond the recess in the projection or extension 85 to be engaged by a projection 87 carried by and extending laterally beyond the rear face of the gear 80. The spring 82 in the drum 74 is arranged in such a manner that it will tend normally to move the projection 87 on the gear 80 into 110 engagement with the elastic member 86 carried by the projection 85, which acts as an elastic bumper upon the return of the gear.

Secured to the other extremity of the hub 73 of the drum 74 is an operating handle 88, 115 by means of which the hub 73 of the drum 74 may be rotated about the stud or axle 72. The gear 80 is arranged in proximity to the worm gear 49 on the shaft 48 and is of such a diameter that when the operating handle 120 88 is in the position shown in Fig. 7, the gear 80 will be moved out of mesh with the gear 49. If, however, the operating handle 88 is moved from the position shown in Fig. 7, toward the left, the hub 73 of the drum 125 74 will be rotated eccentrically about the stud or axle 72, which will bodily shift the gear 80 so that the peripheral teeth thereof will be moved into mesh with the worm gear 49. In this position, it will be apparent 130

that when the shaft 48 is rotated in the manner which is already described, by the handle 69, the gear 80 will also be rotated. The gears 49 and 80 are so arranged that when the shaft 66 is being rotated in the direction to cause the liquid to be discharged from the pump, the gear 80 will be rotated in a direction to create a tension on the coil spring 82 and to also move the projection 87 away from the projection 85 on the element 76. The drum 74 thus described is connected with the valve 31 and serves as a means for opening the valve to permit the liquid to flow through the valve housing 27 when the handle 88 is moved from the position shown in Fig. 7 toward the left and for this purpose there is provided a bar or rod 89 which passes through the tubular member 44 with one of its extremities 20 threaded as at 90 and which extremity projects into the casing 36. An adjustable sleeve 91 is threaded on this extremity of the rod 89 and is preferably provided with a recess 92 into which the free extremity of the 25 valve stem 34 of the valve 31 projects.

A lock nut 93 may be provided on the bar or rod 89 for locking the sleeve 91 against accidental adjustment. The upper extremity of this bar or rod 89 projects through the 30 boss 45 on the housing 46 and into the housing through an opening in the bottom thereof. This extremity of the bar or rod terminates adjacent the face of the drum 74 and is bifurcated as at 94. Into this bifurcated 35 portion a lug or projection 95 on the drum 74 projects and serves as a means whereby the extremity of the bar or rod 89 is connected to the drum. This projection 95 is preferably provided with a head to prevent 40 accidental and lateral disengagement of the bar or rod with respect to the drum. Thus it will be apparent that when the handle 88 is moved to the left from the position shown in Fig. 7 and the drum 74 is rotated, the projection 95 thereon will force the bar or rod 89 downwardly to unseat the valve 31 against the tension of the elastic member 32 and the valve 31 will remain open so long as the parts are in the position just 45 described. It will also be apparent that if the handle 88 should be released, the elastic member 32 would tend to move the handle back into the position shown in Fig. 7 from the adjusted position and thereby move the 50 gear 80 out of mesh with the gear 49 and the projection 87 of the gear into engagement with the spring 86. In order to prevent this operation, and to maintain the gears 80 and 49 in mesh for a predetermined 55 period, without necessitating the operator holding the handle 88 and the parts in this adjusted position, suitable mechanism for locking the parts in the adjusted position to maintain the gears 80 and 49 in mesh and 60 the valve 31 open, and for also automatically

releasing these parts to permit the valve 31 to close at a predetermined period, will now be described.

Projecting radially from the drum 74 is an arm or extension 96 which is provided with a shoulder 97 and this arm 96 is so positioned that when the handle 88 is adjusted to the left from the position shown in Fig. 7 to open the valve 31, the shoulder 97 will be engaged by a spring controlled dog 98 which is pivotally mounted preferably upon the bracket or element 76.

Carried by the face of the gear 80 is an extension 99 mounted in which is an adjustable element 100 preferably in the form 80 of a screw or bolt. The dog 98 is provided with an arm 101 which normally projects in the path of the movement of the element 100.

As has already been described, when the parts are adjusted to move the gear 80 in mesh with the gear 49, the valve 31 will be held open and will be locked open by the engagement of the shoulder 97 with the dog 98. It has also been stated that when the shaft 48 rotates, the gear 49 will operate to move the gear 80 in a direction to create a tension on the spiral 82. This direction of rotation of the gear 80 is indicated by the arrow in Fig. 7. After the parts have been 95 thus adjusted and locked, they will remain in this position until the element 100 engages the arm 101 on the dog 98. A further movement of the gear 80 in the same direction will then cause the element 100 to rock the dog 98 so as to move the latter out of engagement with the shoulder 97 on the arm 96 against the tension of the elastic member 102 and the drum 74 will be then released. When thus released, the tension 100 which has been created upon the elastic members 82 and 32 will move the drum 74 in a clockwise direction. As this drum is mounted eccentrically upon the stub or axle 72 it will be manifest that this reverse rotation of the drum will cause the gear 80 to be bodily moved out of mesh with the gear 49. When out of mesh, the spring 82 will operate on the gear 80 to rotate it in a direction to cause the projection 87 to move into 115 engagement with the elastic member 86 carried by the projection 85.

By adjusting the sleeve 91 on the end of the bar or rod 89 it will be apparent that the time of opening of the valve 31 may be 120 varied and by providing the bifurcated extremity on the bar or rod 89 a loose connection will be formed between the bar or rod and the spring drum so as to permit the springs or elastic members 32, 82, to operate 125 without interfering with each other.

The housing 46 is provided with a closure 104 by means of which the controlling mechanism thus described may be completely incased and locking mechanism 130

designated generally by the reference numeral 105^a is provided for locking the closure closed and this locking mechanism may be of any type, preferably of a type 5 wherein a key is employed to actuate the same.

It is thought that the operation of this improved apparatus will be clearly understood from the description given and with 10 this improved construction it will be manifest that the controlling mechanism may be set in the manner described by any authorized person and when thus set the casing 46 may be locked. The pump may be thus set 15 into operation by the operation of the handle 69 and will continue to actuate by the operation of this handle to discharge liquid through the pipe 26, which latter may be arranged to convey it to any desired point 20 of use, until a predetermined quantity has been discharged. This predetermined quantity may be controlled by the adjustment of the element 100 to vary its time of engagement with the arm 101 of the dog 98. When 25 this element does engage this arm 101, it will be manifest that the dog will be tripped, the parts released, and the valve 81 will be seated by the elastic member 82 and this elastic member 82 will also operate to rotate the spring drum 74 about the stud or 30 axle 72 in a direction to move the gear 80 out of mesh with the gear 49.

In order that the pump may be employed for other purposes, such, for instance, as 35 discharging a quantity of liquid at the pump, a discharge nozzle 105 of any desired or suitable type may be employed (see particularly Figs. 1, 2 and 3). This nozzle is connected with an extension 106 leading 40 from the discharge outlet 25 of the pump cylinder and this nozzle 105 has communication with the pump cylinder or discharge thereof preferably on the side of the valve housing 27 adjacent the inlet of said 45 housing.

Thus it will be manifest that even though the valve 81 is seated to prevent the liquid from being discharged through the pipe 26, liquid may be discharged from the pump 50 through the extension 106 and valve 105 when the latter is open.

What is claimed as new is—

1. The combination of a pump, a discharge outlet therefor, mechanism for operating the pump, controlling means for the outlet, means whereby the said controlling means may be set to open the outlet, means for automatically actuating the said controlling means to close the outlet when a predetermined quantity of liquid has been discharged therethrough, a second discharge outlet for the pump, and means for controlling the second said outlet. 60

2. The combination of a pump, a discharge outlet therefor, mechanism for oper-

ating the pump, controlling means for the outlet, means whereby the said controlling means may be set to open the outlet, means operatively related to the pump operating means for automatically actuating the said 70 controlling means to close the outlet when a predetermined quantity of liquid has been discharged therethrough, a second discharge outlet for the pump, and manually actuated means for controlling the second said outlet. 75

3. The combination of a pump, a discharge outlet therefor, mechanism for operating the pump, controlling means for the outlet, means whereby the said controlling means may be set to open the outlet, means 80 for automatically actuating the controlling means to close the outlet when a predetermined quantity of liquid has been discharged therethrough, and means for inclosing the last two recited means embodying means 85 whereby access may be had thereto.

4. The combination of a pump, a discharge outlet therefor, mechanism for operating the pump, controlling means for the outlet, means whereby the said controlling 90 means may be set to open the outlet, means for automatically actuating the controlling means to close the outlet when a predetermined quantity of liquid has been discharged therethrough, means whereby access 95 to the said controlling means may be prevented, a second discharge outlet and a manually actuated valve for controlling the last recited outlet and operable independently with respect to the first recited controlling means. 100

5. The combination of a pump, a discharge outlet therefor, mechanism for operating the pump, controlling means for the outlet embodying a valve, means tending 105 normally to close the valve, and means whereby the valve may be opened against the pressure of the closing means and maintained open, means for automatically releasing the valve when a predetermined amount 110 of liquid has been discharged, means for preventing the actuation of the valve opening means, and a discharge faucet operable independently of the valve operating means. 115

6. The combination of a pump, a discharge outlet therefor, mechanism for operating the pump, controlling means for the outlet embodying a valve, means tending normally to close the valve, and means whereby the valve may be opened against 120 the pressure of the closing means and maintained open, variable means for automatically releasing the valve when a predetermined amount of liquid has been discharged, means preventing the actuation of the valve 125 opening means, and a discharge for the pump manually operable independent of the valve operating means.

7. The combination of a pump, a discharge outlet therefor, mechanism for op- 130

- erating the pump, controlling means for the outlet embodying a valve, means tending normally to close the valve, means whereby the valve may be opened against the pressure of the closing means and maintained open, means for automatically releasing the valve when a predetermined amount of liquid has been discharged, means for preventing actuation of the valve opening means, means other than the said valve closing means for rendering the valve releasing mechanism inactive when the valve is closed, and a second discharge operable independently of the said valve.
8. The combination of a pump, a discharge outlet therefor, mechanism for operating the pump, controlling means for the outlet embodying a valve, means tending normally to close the valve, means for opening the valve against the pressure of the last recited means and embodying mechanism for locking the valve open, means for automatically releasing the valve when a predetermined amount of liquid has been discharged, a second discharge outlet, and means operable independently with respect to the said valve, for controlling the last recited discharge outlet.
9. The combination of a pump, a discharge outlet therefor, mechanism for operating the pump, controlling means for the outlet embodying a valve, means tending normally to close the valve, means for opening the valve against the pressure of the last recited means and embodying mechanism for locking the valve open, means for automatically releasing the valve when a predetermined amount of liquid has been discharged, means other than the said valve closing means for rendering the valve releasing means inactive and means for preventing actuation of the valve opening and the valve releasing means.
10. The combination of a pump, a discharge outlet therefor, mechanism for operating the pump, controlling means for the outlet embodying a valve, means tending normally to close the valve, means for opening the valve against the pressure of the last recited means and embodying mechanism for locking the valve open, means for automatically releasing the valve when a predetermined amount of liquid has been discharged, means other than the said valve closing means for rendering the valve releasing means inactive, means for preventing actuation of the valve opening and the valve releasing means for maintaining both inactive while the pump actuating means remains active, and a second discharge independently operable through which the liquid may flow when the first recited outlet is closed.
11. The combination of a pump, a discharge outlet therefor, mechanism for actuating the pump, means tending normally to close the outlet, means for actuating the last said means to open the outlet and embodying mechanism for retaining the first recited means in a position to maintain the outlet open, and means for releasing the first said means for closing the outlet when a predetermined quantity of liquid has been discharged, the said releasing means embodying a shaft having a constant direction of rotation and a second shaft operatively connected with the first said shaft and rotatable forwardly and backwardly.
12. The combination of a pump, a discharge outlet therefor, mechanism for actuating the pump, means tending normally to close the outlet, means for actuating the last said means to open the outlet and embodying mechanism for retaining the first recited means in a position to maintain the outlet open, means for releasing the first said means for closing the outlet when a predetermined quantity of liquid has been discharged, the said releasing means embodying a shaft having a constant direction of rotation and a second shaft operatively connected with the first said shaft and rotatable forwardly and backwardly, and means operatively connecting one of the said shafts with the pump actuating mechanism.
13. The combination of a pump, a discharge outlet therefor, mechanism for actuating the pump, means tending normally to close the outlet, means for actuating the last said means to open the outlet and embodying mechanism for retaining the first recited means in a position to maintain the outlet open, means for releasing the first said means for closing the outlet when a predetermined quantity of liquid has been discharged, the said releasing means embodying a shaft having a constant direction of rotation and a second shaft operatively connected with the first said shaft and rotatable forwardly and backwardly, a second discharge outlet, and means for controlling the latter independently with respect to the first recited outlet and while the latter is closed.
14. The combination of a pump, a discharge outlet therefor, mechanism for actuating the pump, means tending normally to close the outlet, means for actuating the last said means to open the outlet and embodying mechanism for retaining the first recited means in a position to maintain the outlet open, and means for releasing the first said means for closing the outlet when a predetermined quantity of liquid has been discharged, the said releasing means embodying a shaft having a constant direction of rotation, a second shaft rotatable forwardly and backwardly and means connecting the first said shaft directly with the second said shaft.

15. The combination of a pump, a discharge outlet therefor, mechanism for actuating the pump, means tending normally to close the outlet, means for actuating the last said means to open the outlet and embodying mechanism for retaining the first recited means in a position to maintain the outlet open, and means for releasing the first said means for closing the outlet when a predetermined quantity of liquid has been discharged, the said releasing means embodying a shaft having a constant direction of rotation, a second shaft arranged end to end with the first said shaft and rotatable forwardly and backwardly, and clutch mechanism connecting the adjacent ends of the shafts.
16. The combination of a pump, a discharge outlet therefor, means for operating the pump, means tending normally to close the outlet, means for opening the outlet against the pressure of the last said means and for maintaining the outlet open, the third recited means embodying gears movable relatively, means for releasing the outlet opening means when a predetermined quantity of liquid has been discharged, and means embodying the second recited means for imparting such relative movement to the gears to place them out of mesh.
17. The combination of a pump, a discharge outlet therefor, means for operating the pump, means tending normally to close the outlet, means for opening the outlet against the pressure of the last said means and for maintaining the outlet open, the third recited means embodying gears movable relatively into and out of mesh, means for releasing the outlet opening means when a predetermined quantity of liquid has been discharged, and means embodying the second recited means for imparting such relative movement to the gears to place them out of mesh, one of said gears having a constant direction of rotation.
18. The combination of a pump, a discharge outlet therefor, means for operating the pump, means tending normally to close the outlet, means for opening the outlet against the pressure of the last said means and for maintaining the outlet open, the third recited means embodying gears movable relatively into and out of mesh, means for releasing the outlet opening means when a predetermined quantity of liquid has been discharged, means embodying the second recited means for imparting such relative movement to the gears to place them out of mesh, one of said gears having a constant direction of rotation, and an element adapted for rotation forwardly and backwardly operatively connected with the last said gear for imparting rotation thereto.
19. The combination of a pump, a discharge outlet therefor, means for operating the pump, means tending normally to close the outlet, means for opening the outlet against the pressure of the last said means and for maintaining the outlet open, the third recited means embodying gears movable relatively into and out of mesh, means for releasing the outlet opening means when a predetermined quantity of liquid has been discharged, means embodying the second recited means for imparting such relative movement to the gears to place them out of mesh, and means operatively connecting the said element with the pump operating means.
20. The combination of a pump, a discharge outlet therefor, means for operating the pump, means tending normally to close the outlet, means for opening the outlet against the pressure of the last said means and embodying gears relatively movable into and out of mesh and also mechanism for locking the outlet open, one of said gears having a constant direction of rotation and adapted to rotate the other gear in one direction when in mesh, means operatively related to the said other gear for releasing the outlet opening means when the gear is thus rotated, means embodying the second recited means and operatively related to the last recited means for moving one of the gears out of mesh with the other, and means for imparting rotation to the said other gear in the opposite direction when the gears are out of mesh.
21. The combination of a pump, a discharge outlet therefor, means for operating the pump, means tending normally to close the outlet, means for opening the outlet against the pressure of the last said means and embodying gears one of which is movable into and out of mesh with the other and also embodying mechanism for locking the outlet open, one of said gears having a constant direction of rotation and adapted to rotate the other gear in one direction when in mesh, adjustable means operatively related to the said other gear for releasing the outlet opening means when the gear is thus rotated, means operatively related to the last recited means and with which the second recited means co-operates for moving the gear out of mesh, and means for imparting rotation to the said other gear in the opposite direction when the gears are out of mesh.
22. The combination of a pump, a discharge outlet therefor, means for operating the pump, means tending normally to close the outlet, means for opening the outlet against the pressure of the last said means and embodying gears one of which is movable into and out of mesh and embodying mechanism for locking the outlet open, one of said gears having a constant direction of rotation and adapted to rotate the other gear in one direction when in mesh, means opera-

tively related to the said other gear for releasing the outlet opening means when the gear is thus rotated, means operatively related to the last recited means and with which the second recited means coöperates for moving the gear out of mesh, means for imparting rotation to the said other gear in the opposite direction when the gears are out of mesh, and means for limiting the degree of rotation of the said other gear by the last recited means.

23. The combination of a pump, a discharge outlet therefor, means for operating the pump, means tending normally to close the outlet, means for opening the outlet against the pressure of the last said means embodying gears one of which is movable into and out of mesh and also embodying mechanism for locking the outlet open, one of said gears having a constant direction of rotation and adapted to rotate the other gear in one direction when in mesh, means operatively related to the said other gear for releasing the outlet opening means when the gear is thus rotated, means operatively related to the last recited means and with which the second recited means coöperates for moving the gear out of mesh, means for imparting rotation to the said other gear in the opposite direction when the gears are out of mesh, and stop mechanism for limiting the degree of rotation of the said other gear by the last recited means. said stop mechanism embodying a cushioning device.

24. The combination of a pump, a discharge outlet therefor, means for operating the pump, means tending normally to close the outlet, means for opening the outlet against the pressure of the last said means embodying gears one of which is movable into and out of mesh, and also embodying mechanism for locking the outlet open, one of said gears having a constant direction of rotation and adapted to rotate the other gear in one direction when in mesh, adjustable means operatively related to the said other gear for releasing the outlet opening means when the gear is thus rotated, means operatively related to the last recited means and embodying the second recited means for moving the gear out of mesh, and means for imparting rotation to the said other gear in the opposite direction when the gears are out of mesh.

25. The combination of a valve, means tending normally to close the valve, means for opening the valve embodying a gear, a second gear with which the first gear coöperates, said gears being relatively movable whereby they may be moved into and out of mesh, means operatively connecting one of the gears with the valve whereby such relative movement to cause the gears to mesh will open the valve, and the movement of the gears out of mesh will permit the valve

to close, and means for locking the gears in mesh.

26. The combination of a valve, means tending normally to close the valve, means for opening the valve embodying a gear, a second gear with which the first gear coöperates, said gears being relatively movable whereby they may be moved into and out of mesh, means operatively connecting one of the gears with the valve whereby such relative movement to cause the gears to mesh will open the valve, and the movement of the gears out of mesh will permit the valve to close, the second said means embodying means for locking the gears in mesh, and means operatively related to one of the gears to rotate it.

27. The combination of a valve, means tending normally to close the valve, means for opening the valve embodying a gear, a second gear with which the first gear coöperates, said gears being relatively movable whereby they may be moved into and out of mesh, means operatively connecting one of the gears with the valve whereby such relative movement to cause the gears to mesh will open the valve, and the movement of the gears out of mesh will permit the valve to close, the second recited means embodying means for locking the gears in mesh, means for automatically unlocking the gears to permit them to be moved out of mesh, and power mechanism for imparting rotation to the gears when in mesh.

28. The combination of a valve, means tending normally to close the valve, means for opening the valve embodying a gear, a second gear with which the first gear coöperates, said gears being relatively movable whereby they may be moved into and out of mesh, means operatively connecting one of the gears with the valve whereby such relative movement to cause the gears to mesh will open the valve, and the movement of the gears out of mesh will permit the valve to close, means embodying the second recited means for locking the gears in mesh, and means for automatically unlocking the gears to permit them to be moved out of mesh, one of said gears having a constant direction of rotation.

29. The combination of a valve, means tending normally to close the valve, means for opening the valve embodying a gear, a second gear with which the first gear coöperates, said gears being relatively movable whereby they may be moved into and out of mesh, means operatively connecting one of the gears with the valve whereby such relative movement to cause the gears to mesh will open the valve, and the movement of the gears out of mesh will permit the valve to close, means embodying the second recited means for locking the gears in mesh, and means for automatically unlocking the gears

to permit them to be moved out of mesh, one of said gears having a constant direction of rotation and adapted to rotate the other gear in one direction, said other gear 5 being rotated in the opposite direction by the closing action of the valve when the gears are out of mesh.

30. The combination of a valve, means tending normally to close the valve, means 10 for opening the valve embodying a gear, a second gear with which the first gear cooperates, said gears being relatively movable whereby they may be moved into and out of mesh, means operatively connecting one of 15 the gears with the valve whereby such relative movement to cause the gears to mesh will open the valve, and the movement of the gears out of mesh will permit the valve to close, means embodying the second recited 20 means for locking the gears in mesh, means for automatically unlocking the gears to permit them to be moved out of mesh, one of said gears having a constant direction of rotation and adapted to rotate the other 25 gear in one direction, said other gear being rotated in the opposite direction upon the closing action of the valve when the gears are out of mesh, and means for limiting the degree of the last recited rotation of the 30 gear.

31. The combination of a valve, operating mechanism therefor embodying a gear, a second gear, a movable eccentric support for the said second gear by whose movement 35 the gear may be bodily moved into and out of mesh with the first said gear, means whereby the said bodily movement of the gear in one direction will open the valve, means for thus moving the last said gear, 40 means for bodily moving the gear in the opposite direction and out of mesh with the other gear to permit the valve to close, and means for automatically controlling the last said bodily movement of the gear.

45. 32. The combination of a valve, operating mechanism therefor embodying a gear, a second gear, a movable eccentric support for the said second gear by whose movement the gear may be bodily moved into and out of 50 mesh with the first said gear, means whereby the said bodily movement of the gear in one direction will open the valve, means for thus moving the last said gear, means for bodily moving the gear in the opposite direction 55 and out of mesh with the other gear to permit the valve to close, and means for automatically controlling the last said bodily movement of the gear.

33. The combination of a valve, operating 60 mechanism therefor embodying a gear, a second gear, a movable eccentric support for the said second gear by whose movement the gear may be bodily moved into and out of mesh with the first said gear, means whereby 65 the said bodily movement of the gear in one

direction will open the valve, means for thus moving the last said gear, means for bodily moving the gear in the opposite direction and out of mesh with the other gear to permit the valve to close, and means operatively related to one of the gears for automatically controlling the last said bodily movement of the gear. 70

34. The combination of a valve, operating mechanism therefor embodying a gear, a second gear, a movable eccentric support for the said second gear by whose movement the gear may be bodily moved into and out of mesh with the first said gear, means whereby the said bodily movement of the gear in one direction will open the valve, means for thus moving the last said gear, means for bodily moving the gear in the opposite direction and out of mesh with the other gear to permit the valve to close, and means operatively related to the eccentrically supported gear for automatically controlling the last said bodily movement of the gear. 80 85

35. The combination of a valve, operating mechanism therefor embodying a gear, a second gear, a movable eccentric support for the said second gear by whose movement the gear may be bodily moved into and out of mesh with the first said gear, means whereby the said bodily movement of the gear in one direction will open the valve, means for thus moving the last said gear, means for bodily moving the gear in the opposite direction and out of mesh with the other gear to permit the valve to close, and means carried by and adjustable relatively to one of the gears for automatically controlling the last said bodily movement of the gear. 90 95 100

36. The combination of a valve, operating mechanism therefor embodying a gear, a second gear, a movable eccentric support for the said second gear by whose movement the gear may be bodily moved into and out of mesh with the first said gear, means whereby the said bodily movement of the gear in one direction will open the valve, means for thus moving the last said gear, means for bodily moving the gear in the opposite direction and out of mesh with the other gear to permit the valve to close, and means carried by the eccentrically supported gear and adjustable relatively thereto for automatically controlling the last said bodily movement of the gear. 110 115 120

37. The combination of a valve, a pair of gears, one of said gears being fixed and having a constant direction of rotation, the other of said gears being supported for movement into and out of mesh with the first said gear and adapted for rotation forwardly and backwardly, means for moving the second gear into mesh with the first said gear, mechanism operating in unison with the movement of the gears into mesh for 125 130

- opening the valve and for maintaining the same open while the gears are in mesh, means for locking the gears in mesh, means controlled by the rotating movement of the 5 second said gear in one direction for releasing the locking means, and means embodying said opening mechanism for moving the said gears out of mesh when unlocked, whereby the valve may be closed.
- 10 38. The combination of a valve, a pair of gears, one of said gears being fixed and having a constant direction of rotation, the other of said gears being supported for movement into and out of mesh with the 15 first said gear and adapted for rotation forwardly and backwardly, means for moving the second gear into mesh with the first said gear, mechanism operating in unison with the movement of the gears into mesh for opening the valve and for maintaining the same open while the gears are in mesh, means for locking the gears in mesh, means controlled by the rotating movement of the 20 second said gear in one direction for releasing the locking means, means embodying the said opening mechanism for moving the gears out of mesh when unlocked and for closing the valve, and means for rotating the second said gear in the opposite direction.
- 25 39. The combination of a valve, a pair of gears, one of said gears being fixed and having a constant direction of rotation, the other of said gears being supported for movement into and out of mesh with the 30 first said gear and adapted for rotation forwardly and backwardly, means for moving the second gear into mesh with the first said gear, mechanism operating in unison with the movement of the gears into mesh for opening the valve and for maintaining the same open while the gears are in mesh, means for locking the gears in mesh, means controlled by the rotating movement of the 35 second said gear in one direction for releasing the locking means, means embodying the said opening mechanism for moving the gears out of mesh when unlocked and for closing the valve, and means for rotating the second said gear in the opposite direction, and
- 40 45 50 40. The combination of a valve, a fixed gear, a second gear mounted eccentrically for bodily movement into and out of mesh with the fixed gear, means tending normally to close the valve and to move the gears out of mesh, means for moving the gears into mesh and against the pressure of the first said means, means operating in unison with the second said means for opening the valve, means embodying the second recited means for locking the valve open and the gears in mesh, the second said gear being adapted for rotary motion in both directions, adjustable means for releasing the locking means after a predetermined movement of the second gear and when the last said gear is rotated in one direction, and means whereby the second said gear will be placed under tension when thus rotated for rotating said gear in the opposite direction when the gears are moved out of mesh.
- 45 50 55 60 65 40. The combination of a valve, a fixed gear having a constant direction of rotation, a second gear mounted eccentrically for bodily movement into and out of mesh with the fixed gear, means tending normally to close the valve and to move the gears out of mesh, means for moving the gears into mesh and against the pressure of the first said means, means operating in unison with the second said means for opening the valve, means embodying the second recited means for locking the valve open and the gears in mesh, the second said gear being adapted for rotary motion in both directions, adjustable means for releasing the locking means after a predetermined movement of the second gear and when the last said gear is rotated in one direction, and means whereby the second said gear will be placed under tension when thus rotated for rotating said gear in the opposite direction when the gears are moved out of mesh.

a predetermined movement of the second gear and when the last said gear is rotated in one direction, and means whereby the second said gear will be placed under tension when thus rotated for rotating said gear in the opposite direction when the gears are moved out of mesh.

41. The combination of a valve, a fixed gear, a second gear mounted eccentrically for bodily movement into and out of mesh with the fixed gear, means tending normally to close the valve and to move the gears out of mesh, means for moving the gears into mesh and against the pressure of the first said means, means operating in unison with the second said means for opening the valve, means embodying the second recited means for locking the valve open and the gears in mesh, the second said gear being adapted for rotary motion in both directions, means for releasing the locking means after a predetermined movement of the second gear and when the last said gear is rotated in one direction, means whereby the second said gear will be placed under tension when thus rotated for rotating said gear in the opposite direction when the gears are moved out of mesh, and means for limiting the rotation of the last said gear in the said opposite direction.

42. The combination of a valve, a fixed gear, a second gear mounted eccentrically for bodily movement into and out of mesh with the fixed gear, means tending normally to close the valve and to move the gears out of mesh, means for moving the gears into mesh and against the pressure of the first said means, means operating in unison with the second said means for opening the valve, means embodying the second recited means for locking the valve open and the gears in mesh, the second said gear being adapted for rotary motion in both directions, adjustable means for releasing the locking means after a predetermined movement of the second gear and when the last said gear is rotated in one direction, and means whereby the second said gear will be placed under tension when thus rotated for rotating said gear in the opposite direction when the gears are moved out of mesh.

43. The combination of a valve, a fixed gear having a constant direction of rotation, a second gear mounted eccentrically for bodily movement into and out of mesh with the fixed gear, means tending normally to close the valve and to move the gears out of mesh, means for moving the gears into mesh and against the pressure of the first said means, means operating in unison with the second said means for opening the valve, means embodying the second recited means for locking the valve open and the gears in mesh, the second said gear being adapted for rotary motion in both directions, adjustable means for releasing the locking means after a predetermined movement of the second gear and when the last said gear is rotated in one direction, and means whereby the second said gear will be placed under tension when thus rotated for rotating said gear in the opposite direction when the gears are moved out of mesh.

able means for releasing the locking means after a predetermined movement of the second gear and when the last said gear is rotated in one direction, and means whereby 5 the second said gear will be placed under tension when thus rotated for rotating said gear in the opposite direction when the gears are moved out of mesh.

44. The combination of a valve, a fixed 10 gear having a constant direction of rotation, a power shaft rotatable forwardly and backwardly, connecting mechanism between said shaft and gear, a second gear mounted eccentrically for bodily movement into and 15 out of mesh with the fixed gear, means tending normally to close the valve and to move the gears out of mesh, means moving the gears into mesh and against the pressure of the first said means, means operating in unison with the second said means for opening 20 the valve, means embodying the second recited means for locking the valve open and the gears in mesh, the second said gear being adapted for rotary motion in both directions, 25 means for releasing the locking means after a predetermined movement of the second gear and when the last said gear is rotated in one direction, and means whereby the second said gear will be placed under 30 tension when thus rotated for rotating said gear in the opposite direction when the gears are moved out of mesh.

45. The combination of a valve, a fixed gear, a second gear mounted eccentrically 35 for bodily movement into and out of mesh with the fixed gear, means tending normally to close the valve and to move the gears out of mesh, means for moving the gears into mesh and against the pressure of the first 40 said means, means operating in unison with the second said means for opening the valve, means embodying the second recited means for locking the valve open and the gears in mesh and embodying a catch, the second said 45 gear being adapted for rotation in both directions, a tripping member carried by one of the gears for tripping the catch after a predetermined movement of the second gear and when the last said gear is rotated in 50 one direction, and means for rotating the last said gear in the opposite direction when the gears are out of mesh for positioning the tripping member with respect to the catch.

46. The combination of a valve, a fixed

gear, a second gear mounted eccentrically 55 for bodily movement into and out of mesh with the fixed gear, means tending normally to close the valve and to move the gears out of mesh, means for moving the gears into mesh and against the pressure of the first said means, means operating in unison with the second said means for opening the valve, means embodying the second recited means for locking the valve open and the gears in mesh and embodying a catch, 60 the second said gear being adapted for rotation in both directions, a tripping member carried by one of the gears for tripping the catch after a predetermined movement of the second gear and when the last said gear 70 is rotated in one direction, and means for rotating the last said gear in the opposite direction when the gears are out of mesh for positioning the tripping member with respect to the catch. 75

47. The combination of a valve, a fixed gear, a second gear mounted eccentrically for bodily movement into and out of mesh with the fixed gear, means tending normally to close the valve and to move the gears 80 out of mesh, means for moving the gears into mesh and against the pressure of the first said means, means operating in unison with the second said means for opening the valve, means embodying the second recited 85 means for locking the valve open and the gears in mesh and embodying a catch, the second said gear being adapted for rotation in both directions, a tripping member carried by one of the gears for tripping the 90 catch after a predetermined movement of the second gear and when the last said gear is rotated in one direction, means for rotating the last said gear in the opposite direction when the gears are out of mesh for 95 positioning the tripping member with respect to the catch, and stop mechanism for limiting the movement of the gear in the said opposite direction.

In testimony whereof I have signed my 100 name to this specification, in the presence of two subscribing witnesses, on this 20th day of March A. D. 1911.

ANDREW D. WYCKOFF.
